Patented July 9, 1929.

Des. 78,960

UNITED STATES PATENT OFFICE.

JUSTIN GEORGE FEINBERG, OF CHICAGO, ILLINOIS, ASSIGNOR TO HEYWOOD-WAKEFIELD COMPANY, OF BOSTON, MASSACHUSETTS, A CORPORATION OF MASSACHUSETTS.

DESIGN FOR A FOLDING THEATER CHAIR.

Application filed November 21, 1927. Serial No. 24,223. Term of patent 7 years.

To all whom it may concern:

Be it known that I, JUSTIN GEORGE FEINBERG, a citizen of the United States, residing at Chicago, in the county of Cook and State of Illinois, have invented a new, original, and ornamental Design for a Folding Theater Chair, of which the following is a specification, reference being had to the accompanying drawing, forming part thereof, in which the figure is a perspective view of a folding theater chair showing my new design.

I claim:

The ornamental design for a folding theater chair, as shown.

Dated this 10th day of November 1927.

JUSTIN GEORGE FEINBERG.
